UNITED STATES PATENT OFFICE

GEORGE TEZARAVICS, OF SPRING HILL MINES, NOVA SCOTIA, CANADA

AUTOMATIC TRACK SWITCH

Application filed September 13, 1929. Serial No. 392,397.

This invention relates to certain new and useful improvements in automatic track switches.

The primary object of the invention is to provide an automatic track switch wherein the switch points have operative means engageable with the swinging ends thereof to be operated by abutments depending from railroad rolling stock for engagement with track trips.

A further object of the invention is to provide an automatic track switch of the above type wherein the switch points are automatically shifted to provide clear rails for rolling stock approaching the switch from the pivoted ends of the switch point, the switch point in this instance being operated by trip devices disposed adjacent the track rails and operated by the wheels of rolling stock.

With the above and other objects in view that will become apparent as the nature of the invention is better understood, the same consists in the novel construction, combination and arrangement of parts to be herein-
after more fully described and then claimed.

In the accompanying drawings, to which reference is had by like characters designating parts throughout the several views and in which the preferred embodiment of the invention is illustrated,

Figure 1 is a fragmentary top plan view of a railroad track constructed in accordance with the present invention showing the switch points for the track rails and the trip devices located beyond opposite ends of the switch points for shifting the latter,

Figure 2 is a fragmentary top plan view of the track structure showing one switch point engaged with a rail and the other switch point spaced from the opposite rail and in reverse positions illustrated by dotted lines, together with part of the operating mechanism therefor,

Figure 3 is a fragmentary top plan view of the switch points in reverse positions with respect to Figure 2,

Figure 4 is a fragmentary vertical longitudinal sectional view taken on line 4—4 of Figure 1,

Figure 5 is a fragmentary vertical longi-

tudinal sectional view taken on line 5—5 of Figure 1,

Figure 6 is a vertical cross-sectional view taken on line 6—6 of Figure 1 showing the track rails, the operating rods for the switch points and the trip levers engaged with the operating rods.

Figure 7 is a vertical cross-sectional view taken on line 7—7 of Figure 1 showing the semaphore or light signal operatively engaged with the switch points,

Figure 8 is a vertical cross-sectional view taken on line 8—8 of Figure 1 showing the tie bar supporting the swinging ends of the switch points and the operating arms for the tie bar.

Figure 9 is a vertical cross-sectional view taken on line 9—9 of Figure 1 showing a rolling stock wheel engaging a trip arm adjacent one rail to operate the tie bar supporting the switch point ends on approaching the switch points from the pivoted ends, and

Figure 10 is a vertical cross-sectional view, similar to Figure 9 showing the trip adjacent the opposite rail engaged by the wheel of the rolling stock for throwing the switch points in the opposite direction.

Referring more in detail to the accompanying drawings, the reference numerals 1 and 2 designate the rails of the single track while the reference numerals 3 and 4 designate the rails of another track, the rails 3 and 4 merging with the rails 1 and 2 by the provision of switch points 5 and 6 to continue in a single track including the rails 1 and 4 of the two tracks. The rails and switch points are supported on cross ties 7, while the switch points 5 and 6 are pivoted as at 8 to the ends of the track rails 2 and 3 with the free ends moving into contact with the rails 1 and 4 of the single track end of the construction.

The switch points 5 and 6 ride upon the cross ties 7 and are secured at their free swinging ends to the cross reciprocating tie bar 9 movable beneath the track rails as shown in Figure 8. A longitudinal shaft 10 is journaled at each side of the outer rail of the two tracks adjacent the switch points 5 and 6 and said shafts are supported in bearings

11 on the ends of the cross ties 7^a and 7^b. An arm 12 is fixed to each shaft 10 above the tie bar 9 and, depending from said shaft, extends through slotted openings 13 in the ends of the tie bar 9. A track trip of the form best illustrated in Figures 9 and 10 is fixed to each shaft 10 adjacent the switch pivots 8 and outwardly thereof, each track trip comprising a curved arm 14 substantially U-shaped in side elevation with one end 15 thereof fixed to an adjacent shaft 10 while the other end 16 runs upwardly in contact with a rail and is guided by a side groove in the rail as shown at 17 in Figures 9 and 10, the ends 16 being associated with the track rails 2 and 3. The switch point tie bar 9 as shown in Figure 8 has a pivotal connection at one end as at 18 with a link rod 19 that at its other end is associated with mechanism contained in a signal post 20 provided with a signal lamp 21 and rotatable cross head plates 22 constituting a semaphoric signal, the signal being rendered operable upon movement of the switch points and tie bar. The track trip 14 operates the switch points 2 and 3 when rolling stock approaches the switch from the pivoted ends 8 of the switch points.

The switch points 2 and 3 are operated by said track trips, operating rods attached thereto and rolling stock abutments when rolling stock passes over the rails 1 and 4 of the single track construction toward the switch points and such devices are shown in Figures 1 to 7. A pair of switch point moving arms 23 and 24 is pivotally mounted at adjacent ends as at 25 centrally of the cross ties 7^a with the arms 23 and 24 angularly directed towards the free swinging ends of the switch points. A bracket 26 carried by the cross ties 7^a pivotally supports as at 27, a cross arm 28, and a longitudinally shiftable operating rod 29 guided in a bearing 30 upon one of the cross ties 7 as illustrated with the adjacent ends of the arms 28 pivoted thereto as at 31, the operating rods 29 having an angled forward end provided with a pin and slot connection 32 with the outer end of the switch point operating arm 23. The opposite end of the operating rod 29 is slotted as at 33 as shown in Figures 1 and 4 to receive the trip lever 34 extending above the operating rod and pivotally attached at its lower end as at 35 upon a bracket 36 held by the adjacent side of a cross tie 7. The longitudinally shiftable operating rod 37 guided in bearings 38 has its forward end pivotally attached as at 39 to the other end of the cross arm 28 with the rear end slotted as at 40 to receive the trip lever 41 pivotally mounted upon the bracket 42 at the opposite side of the cross tie 7.

Another bracket 43 carried by the cross tie 7^a has pivoted thereto intermediate its ends as at 44, a cross arm 45 to one end of which is pivoted as at 46, one end of a longitudinally shiftable operating rod 47 guided in bear-

ings 38 with the opposite end thereof slotted as at 48 into which a trip lever 49 extends that is pivotally mounted at its other end upon the bracket 50. Another longitudinally shiftable operating rod 51 guided in bearings 52 on a cross tie 7 has the other end of the cross arm 45 pivoted thereto as at 53 with the forward end of the operating rod 51 angularly bent and having a pin and slot connection 54 with the switch point operating arm 24, the rear end of the operating rod 51 being slotted as at 55 through which slot the trip lever 56 extends and is pivoted at its other end upon the bracket 57 on the same side of the cross tie 7 as the bracket 36.

Rolling stock on the track comprising the rails 1 and 4 and travelling in the direction of the free swinging ends of the switch points 5 and 6, should it be desired to shift the switch points from the full line positions shown in Figs. 1 and 3 to the dotted line position shown in Figure 3, manually controlled abutments 60 carried by the rolling stock are lowered for engagement with the trip levers 41 and 56, the operating rods 37 and 51 being longitudinally shifted for moving the outer end of the switch point operating arm 24 away from the switch point 6 and by the provision of the cross arm connection 45 between the operating rods 51 and 47, the latter operating rod 51 is shifted in the reverse direction to position the trip lever 59 for subsequent operation of a following train if desired. Actuation of the trip lever 41 moves the operating rod 37 and by its pivot arm connection 28 with the operating rod 29, the latter is shifted in a reverse direction for moving the switch point operating arm 23 into engagement with the switch point 5 to move the same into engagement with the rail 1 as shown by dotted lines in Figure 3, the switch points 5 and 6 being simultaneously shifted by having their free swinging ends attached to the cross reciprocating tie bar 9. The operation of the trip lever 41 associated with the operating rod 37 causing a reverse reciprocating movement of the operating rod 29 places the trip lever 34 in opposite position to be engaged by a following train if desired together with the trip lever 49. The abutments 60 carried by the rolling stock are manually lowered into engagement with the desired ones of the trip levers, the position of the switch points relative to the track rails 1 and 4 being determined in advance by the semaphore signal elements 21 and 22. Should the switch points 5 and 6 be in the full position shown in Figure 2 and it is desired to shift them to the dotted line position illustrated in said figure, abutments 60 carried by the rolling stock are lowered for engagement with the trip levers 34 and 49 and the reverse operation of the mechanism is effected.

In order to clear either one of the rails 1 or 4 of the free swinging ends of the switch

points 5 or 6 when rolling stock approaches the switch in a direction from the pivoted ends of the switch points, either of the operating arms 14 carried by the shaft 10 is engaged by a wheel W of the rolling stock as will become evident from an inspection of Figures 9 and 10, the depression of either one of the trip arms 14 causing rotation of the shaft 10 carrying the same to cause the 10 arm 12 upon such shaft to shift the tie bar 9 to move the switch points 5 and 6 away from the rails. The trip levers 34, 41, 49 and 56 are operated by rolling stock approaching the switch points from their free swinging 15 ends thereof while the trip arms 14 are operated by rolling stock approaching the switch from the pivoted ends of the switch points.

From the above detailed description of the 20 invention, it is believed that the construction and operation thereof will at once be apparent, and while there is herein shown and described the preferred embodiment thereof, it is to be understood that minor changes may 25 be made in the details of construction, such as will fall within the scope of the invention as claimed.

I claim:—

1. In an automatic railroad switch, pairs 30 of track rails merging into a single pair of rails, a pair of switch points associated with the track rails, train trip operating means spaced from the rails for shifting the switch points and other means associated with the 35 rails and operated by the wheels of rolling stock for shifting the switch points, the train trip operating means being rendered operable when rolling stock approaches the switch from the swinging ends of the switch points 40 and including a pair of arms pivoted on a cross tie at adjacent ends with the outer ends disposed adjacent the switch points, longitudinally extending operating rods for the arms operatively engaged therewith and trip lever 45 engaged with the other ends of the rods adapted to be operated by rolling stock to cause the arms to move the switch points, the other means for operating the switch points including a pair of journalled shafts 50 extending longitudinally of the track, operating means for the shafts including trip arms on the shafts and disposed adjacent the track rails to be operated by the wheels of rolling stock and arms fixed to the shafts 55 engaged with the tie bar connecting the switch points for moving the switch points.

2. In an automatic railroad switch, pairs 60 of track rails merging into a single pair of rails, a pair of switch points associated with the track rails, train trip operating means spaced from the rails for shifting the switch points and other means associated with the rails and operated by the wheels of rolling stock for shifting the switch points, the train 65 trip operating means being rendered oper-

able when rolling stock approaches the switch from the swinging ends of the switch points, the other means for operating the switch points including a pair of journalled shafts 70 extending longitudinally of the track, operating means for the shafts including trip arms on the shafts and disposed adjacent the track rails to be operated by the wheels of rolling stock and arms fixed to the shafts 75 engaged with the tie bar connecting the switch points for moving the switch points.

3. In an automatic railroad switch, pairs 80 of track rails merging into a single pair of rails, a pair of switch points associated with the track rails, the train trip operating means spaced from the rails for shifting the switch points and other means associated with the rails and operated by the wheels of rolling stock for shifting the switch points, the train trip operating means being rendered operable 85 when rolling stock approaches the switch from the swinging ends of the switch points and including a pair of arms pivoted on a cross tie at adjacent ends with the outer ends disposed adjacent the switch points, a 90 pair of link connected operating rods supported on cross ties associated with each arm with one rod of each pair connected to an arm and trip levers associated with the other ends of the operating rods and a tie bar connecting the swinging ends of the switch points whereby the operation of one arm effects operation of both switch points.

In testimony whereof I affix my signature.

GEORGE TEZARAVICS.
